UNITED STATES PATENT OFFICE.

JAMES H. HAMMON, OF VINCENNES, INDIANA

TOOL AND WORK HOLDER AND DRIVER.

1,239,268.

Specification of Letters Patent. Patented Sept. 4, 1917.

Application filed May 29, 1916. Serial No. 100,656.

To all whom it may concern:

Be it known that I, JAMES H. HAMMON, a citizen of the United States, residing at Vincennes, in the county of Knox and State of Indiana, have invented a new and useful Tool and Work Holder and Driver, of which the following is a specification, reference being had to the accompanying drawings and to the letters and figures of reference marked thereon.

This invention relates to holding and driving mechanism for tools and work or articles to be worked on by the tools, the invention having reference more particularly to mechanism that is adaptable for lens-grinding machines or for machines in which cams or eccentricities may be produced.

An object of the invention is to provide an improved mechanism that shall be so constructed as to be useful for various purposes and more particularly for holding and driving tools and work when it is required to produce curved surfaces, such as spherical, cylindrical or toroidal lens faces, or cam or eccentric faces on parts of machinery.

Another object is to provide improved gearing for the above mentioned purposes and means for mounting the gearing on various machines where required, and which shall be capable of doing work expeditiously, accurately and economically.

A still further object is to provide gearing of the above mentioned character that shall be so constructed as to be adapted to be variously driven or operated by means of various types of machines.

With the above mentioned and other objects in view, the invention consists in an improved tool holder and driver and an improved work holder, and gearing adapted for rotating the tool holder and the work holder at one and the same speed; the invention consisting further in the novel parts, and in the combinations and arrangements of parts, as hereinafter particularly described and further set forth in the accompanying claims.

Referring to the drawings, Figure 1 is a front elevation of a suitable type of lens-grinding machine to which the improved mechanism is applied as illustrating one of the purposes of the invention; Fig. 2 is a perspective view of one form of lap that may be used in connection with the im-

proved mechanism; Fig. 3 is a top plan of Fig. 1 partially broken away and minus the lap; Fig. 4 is a central sectional elevation of the grinding machine and improved mechanism; Fig. 5 is a perspective view of a frame member of the improved mechanism; Fig. 6 is a central section of the principal elements of the improved mechanism; Fig. 7 is a perspective view of one of the gear wheels of the mechanism; Fig. 8 is a front elevation of a turning lathe equipped with the invention as illustrating the manner in which the mechanism is adapted to be employed for producing cam or eccentric faces; Fig. 9 is a transverse section approximately on the line A A on Fig. 8; Fig. 10 is a fragmentary section approximately on the line B B on Fig. 8; Fig. 11 is a central section of the improved mechanism slightly modified so as to be adapted for producing cams or eccentricities; Fig. 12 is a sectional detail of the work holder slightly modified so as to hold and drive a milling tool; and Fig. 13 is a perspective view of the elements shown in the preceding figure.

Like characters of reference on the various figures of the drawings indicate like elements or features of construction herein referred to in detail.

The invention being especially valuable in the rapid and accurate shaping of the surfaces of lenses, and particularly such as those designed for eye-glasses, the invention will be first described as applied to a lens-grinding machine which comprises legs or a support 1, upon which is a table 2 that usually supports a pan 3, the table being provided with a journal box 4 in which a vertical driving shaft 5 is rotatably mounted and provided with means for driving it, usually a pulley 6. The table has a suitable standard 7 thereon outside of the pan, the top of the standard being adapted to support parts of the improved mechanism and preferably provided with a stud 8, on which is a nut 9 and a washer 10 under the nut. An arm 11 is arranged upon the standard and extends over the top of the pan 3 and is secured to the standard by means of the stud and the nut, the arm preferably having a slot 12 therein receiving the stud, so that the arm is longitudinally adjustable on the standard. The frame arm 11 is provided with a bearing boss 13 which is provided with a set-screw 14, the boss being

adapted to support a frame member of the mechanism either movably or fixedly to permit adjustment of the member.

For the purposes of the invention as applied to a lens-grinding machine a toothed driving wheel 15 is secured to the shaft 5 above the bottom of the pan 3, the wheel having a hub 16 on its upper side provided with a set-screw 17 whereby the wheel in the present case is secured on the shaft. The top of the hub has a socket 18 therein that is adapted to receive the shank 19 of a lap 20 which may be variously shaped, in some cases having a convex working face 21 adapted for grinding a cylindrical lens face thereon, in some cases having a face 22 that is convex to a greater degree in one direction than in the transverse direction.

The invention includes a frame member 20 which comprises a main portion 23 having a cylindrical portion 24 whereby the member is supported, and when connected with a lens-grinding machine is vertically arranged in the bearing boss 13 and supported 25 for vertical adjustment by means of a collar 25 having a set-screw 26 whereby the collar is adjustably secured on the supporting portion 24, the collar normally resting upon the bearing boss. The main portion 23 and the 30 portion 24 are hollow, a bore 27 extending therethrough and provided with journal boxes 28 and 29 in which a main shaft 30 is rotatably mounted. A toothed wheel 31 is fixed on the shaft 30, preferably being adjustable on the shaft, and the frame arm 11 being properly adjusted, the wheel 30 is maintained in mesh with the driving wheel 15. Another toothed wheel 32 is fixedly secured to the upper portion of the shaft 30 40 and is supported upon the frame portion 23 or the journal box 28. The frame member comprises also an arm 33 which is fixed to the main portion 23 and the arm has a journal box 34 thereon in which is a bore 35 parallel with the main shaft 30. Another toothed wheel 36 is provided which has a journal 37 on its normal under side that is rotatably arranged in the bore 35 of the box 34, the wheel 36 being in mesh with the 50 wheel 32. Preferably the wheels 31 and 32 are of equal diameter and 15 and 36 of equal diameter, it being essential that the wheel 36 be rotated at the same rate as the wheel 15. A bore 38 extends through the wheel 36 and the journal 37, the upper portion of the wheel 36 having a vertical socket 39 therein. The wheel 36 is arranged upon the top of the journal box 34, and the lower portion of the journal 37 is provided with a collar 40 arranged at the under side of the journal box. A shaft or tool-spindle 41 is arranged so as to be longitudinally movable in the bore 38 and has a collar 42 secured to the upper portion thereof, preferably ad-

justable by means of a set-screw 43, the collar being provided with a dowel-pin 44 that extends into the socket 39 whereby to enable the wheel 36 to rotate the shaft 41 and permit the shaft to be adjusted rotatively in the wheel 36, the shaft being readily moved longitudinally by hand by means of the collar. Near its lower end the shaft 41 is provided with a spring-seat 45 on which a spring 46 is arranged that is seated against the lower end of the journal 37, for normally forcing the shaft downward. The lower end of the shaft 41 is provided with a ball-shaped head 47 having a transverse driving pin 48, for rotating a lens holder or block 49 which has a socket therein to receive the head 47 and a slot 50 to receive the pin 48, so that the holder may wobble as it carries the lens blank 51 and rotates it upon the lap.

As illustrating another one of the uses to which the invention is with slight modification adaptable, the mechanism is shown as it may be conveniently applied to a turning lathe, a familiar type of which comprises a bed 52 on which is mounted a head stock 53 and a tail stock 54, the latter supporting a spindle 55 carrying the dead center 56. The live spindle 57 is mounted in the head stock and usually carries the live center 58, the latter in the present case, however, being otherwise carried as will be further explained. A carriage 59 is mounted on the bed 52 and supports a transversely movable slide 60 which carries a tool post 61 provided with a set-screw 62.

The invention includes a spindle section 63 which is provided with a socket 64 that is screwed onto the end of the spindle 57 in the place usually occupied by the face plate of the lathe, so that the spindle section practically constitutes a portion of the driving shaft of the improved mechanism and has a toothed wheel 65 secured thereto and beyond which the face plate 66 of the lathe is screwed onto the spindle extension, the latter receiving the live center 58 in its end. The wheel 65 corresponds in diameter to the wheel 15. The frame member of the improved mechanism is conveniently supported by means of an arm 67 which is secured to the rear side of the bed 52 and extends upward and forwardly and is provided with a bearing boss 68 which receives and rotatively supports the cylindrical portion 24 of the frame member, the portion 24 having a collar 25 on one side and a similar collar 25' on the opposite side of the boss, the collars preferably being adjustably secured in place. The arrangement is such that the portion 24 of the frame member is horizontally supported above the blank 69 that is to be worked on, and which has an arbor 70 that is supported by the lathe centers, the

blank or its arbor being driven by suitable means such as a carrier or dog having connections with the face plate of the lathe. Thus arranged the wheel 31 is maintained in mesh with the wheel 65 for rotating the main shaft 30 and also the wheel 32. In this arrangement the set-screw 14 may be omitted from the bearing boss in order to permit the arm 33 to swing slightly about the shaft 30.

10 The devices whereby the tool is carried and driven are slightly modified when the mechanism is required to operate a milling tool or other type of tool in a lathe or turning machine. A toothed wheel 36' corresponding to the wheel 36 is provided with a journal 37' corresponding to the journal 37 and rotatably mounted in the journal box 34, the wheel 36' being in mesh with the wheel 32. A spindle or shaft 71 is arranged 15 in the wheel 36' and its journal, so as to be rotated thereby and permit longitudinal movement of the spindle, the latter preferably being provided with a spline 72 adapted for the purpose. A suitable milling tool 73 is secured to the spindle or shaft 71 and may be variously constructed as to details and contour, the peripheral contour of the tool determining the peripheral shape of the finished work produced on the blank, as that 20 of a cam or an eccentric. A collar 74 is secured or fixed on the spindle or shaft 71 and between it and the hub of the tool a box 75 is arranged and permits the spindle to rotate therein, the box being arranged in a suitable 25 holder which may comprise a bar 76 that is secured in the tool post of the lathe and provided with guide jaws 77 in which the box 75 is arranged for vertical adjustment, so as to guide the spindle or shaft at one side of 30 and parallel with the axis of rotation of the work 69 or its arbor, and also move the spindle 71 longitudinally in order to feed the tool along the face of the blank to produce a peripheral face 78 corresponding to 35 the peripheral contour of the tool, the feeding being accomplished in the usual manner by the lathe mechanism, and the adjustment of the tool to the work being accomplished through the adjustment of the tool 40 post on the carriage of the lathe as is customary.

45 In the description of the mechanism as employed for different purposes, it has been explained that the driving shaft carries the tool and the driven shaft or spindle carries the work in a lens-grinding machine, and that in the application of the mechanism to a turning machine the tool is carried by the driven shaft or spindle while the work is 50 driven and may be carried by the driving shaft. It is obvious therefore, that either relative arrangement of the work and the tool may be resorted to, according to circumstances or requirements, it being evident

however, that in either case the work holder and the tool holder are rotated on parallel axes at the same speed and in the same direction.

55 In practical use, in the operation of the lens-grinder provided with the improved mechanism, while the lap is rotated the lens blank is arranged on one side of the axis of rotation of the lap and is rotated at the same speed as the lap, and in one and the same direction, and therefore, the curved faces of the work and the lap are always maintained in close contact and with the middle or certain portions of the face of the blank in corresponding relation to the 60 reversely curved portions of the lap, the lap and the blank rotating in the same direction, so that curved lens surfaces, such as spherical, cylindrical or toroidal faces are rapidly and accurately ground or polished. The shafts or spindles are vertically arranged as a matter of expedieney. When the improved mechanism is employed for producing cams or eccentrics the shafts or spindles of the mechanism are more conveniently arranged horizontally, and as described the driven spindle or shaft 71 is controlled as may be desired or required in order that the functions of the improved mechanism shall be performed as contemplated.

65 Having thus described the invention, what is claimed as new is:—

1. A tool and work holder and driver including a supporting-arm having a bearing-boss and having also a base portion to be secured for support on a main support, a frame member having a journal rotatively mounted in the bearing-boss and having also an arm provided with a journal box, a spindle rotatably mounted in the journal box and provided with a toothed driven wheel for rotating it, a main shaft rotatably mounted in the frame member and extending through and also through the journal thereof, a toothed wheel secured to the main shaft and meshing with the driven wheel, a rotatable toothed driving wheel, and a toothed gear wheel secured to the main shaft and meshing with the driving wheel.

2. A tool and work holder and driver including a supporting-arm having a bearing-boss and having also a base portion to be secured to a main support, a frame member having a cylindrical portion and also an arm provided with a journal box, the cylindrical portion being rotatively supported in the bearing-boss, a toothed driven wheel having a hollow journal rotatably mounted in the journal box, a spindle extending through the driven wheel and its journal to be rotated thereby, the spindle being longitudinally-movable and adapted

- 4 to carry and drive a rotary operating device, a main shaft rotatably mounted in the frame member, a toothed wheel secured to the main shaft and meshing with the driven 5 wheel, and driving means connected with the main shaft.
3. A tool and work holder and driver including a supported bearing-boss, a rotatable driving spindle, an extension spindle 10 having a socket connected to the driving spindle and provided with a carrier device, a frame member rotatively mounted in the bearing boss and having an arm thereon and provided with a journal box, a toothed 15 driving wheel secured to the extension spindle, a main shaft rotatably mounted in the frame member, a driven spindle rotatably mounted in the journal box and movable longitudinally therein, a toothed driven 20 wheel for rotating the driven spindle connected with and permitting longitudinal movement of the spindle, a toothed gear wheel secured to the main shaft and meshing with the driven wheel, a toothed gear 25 wheel secured to the main shaft and meshing with the driving wheel, and an operating device secured to the driven spindle.
4. In a tool and work holder and driver, the combination with a main support, and 30 a driving shaft rotatably mounted in the support, of a toothed driving wheel mounted on the driving shaft to be rotated thereby and having a carrier device to be rotated by means of the driving shaft, a frame member supported by the main support and having an arm thereon that is provided with a journal box, a main shaft rotatably mounted in the frame member, a toothed wheel secured to the main shaft and meshing with the 35 driving wheel, a toothed driven wheel having a hollow journal rotatably mounted in the journal box, a toothed wheel secured to the main shaft and meshing with the driven wheel, and a spindle extending 40 through the driven wheel and its journal to be rotated thereby, the spindle being longitudinally-movable and being adapted to carry and drive a rotary operating device.
5. In a tool and work holder and driver, 45 the combination, with a machine frame, a driving spindle on the frame provided with a toothed driving wheel, a carrier device connected with the driving spindle, and an automatic tool-feeding mechanism, of a bearing boss stationarily mounted on the 50 machine frame a frame member rotatively mounted in and supported by the bearing boss, the frame member having a lateral arm thereon provided with a journal box, a main shaft rotatably mounted in the frame member, a toothed gear wheel secured to the main shaft and meshing with the driving wheel, a driven tool carrying spindle rotatably mounted in the journal box and movable longitudinally therein, a toothed driven 55 wheel connected with the driven spindle for rotating the spindle, a toothed gear wheel secured to the main shaft and meshing with the driven wheel, and means for connecting the tool feeding mechanism with the tool-carrying spindle to longitudinally move the tool-carrying spindle.
6. In a tool and work holder and driver, the combination with a bearing boss, of a hollow frame member having a lateral arm 60 near one end thereof, the member having a cylindrical portion extending from the opposite end thereof that is rotatively mounted in the bearing boss, the arm being provided with a journal box, journal bearings 65 supported in the frame member adjacent to the ends thereof, a main shaft rotatively supported by the journal bearings and provided with a driving device, a toothed driven wheel having a hollow journal rotatably 70 mounted in the journal box, a toothed wheel secured to the main shaft and meshing with the driven wheel, a spindle extending through the driven wheel and its journal to be rotated thereby, the spindle being longitudinally-movable, and means for moving the spindle longitudinally in one direction.
